DESIGN.

A. J. STONE.

ORNAMENTATION OF TABLEWARE.

No. 21,115.

Fig. 1. Patented Oct. 13, 1891.

Fig. 2.

UNITED STATES PATENT OFFICE.

ARTHUR J. STONE, OF GARDNER, MASSACHUSETTS, ASSIGNOR TO FRANK W. SMITH, OF SAME PLACE.

DESIGN FOR THE ORNAMENTATION OF TABLE-WARE.

SPECIFICATION forming part of Design No. 21,115, dated October 13, 1891.

Application filed November 26, 1890. Serial No. 372,748. Term of patent 3½ years.

To all whom it may concern:

Be it known that I, ARTHUR J. STONE, a citizen of the United States, residing at Gardner, in the county of Worcester and State of Massachusetts, have invented and produced a new and original Design for the Ornamentation of Table-Ware, of which the following is a specification, reference being had to the accompanying drawings, forming part hereof.

Figure 1 is a side elevation of a coffee-urn, showing my design. Fig. 2 is a side elevation of a sugar-bowl, showing my design.

My design is for the ornamentation of table-ware; and it consists in the somewhat flattened bottom-forming swell and an upper swell connected by an intermediate contracted portion of the body, the upper swell having at its upper part a mount composed of conventionalized shells and leaves, the surface of the receptacle being formed with curved flutings running from the lower swell toward the mount, some of the flutings having bosses at their lower ends upon the surface of the lower swell and others being there extended into curved feather-work and flower-work, as more specifically described below.

A is the lower swell, A' the contracted portion, and A² the upper swell, at the upper end of which is a mount A³, composed of conven-

tionalized shells a' and feathers a². Below 30 the mount the receptacle has curved flutings 1, some of these flutings terminating in bosses 2 upon the surface of swell A and others terminating in curved conventionalized feather-work 3 and flower-work 4. The feather-work 35 and flower-work are grouped together and flanked by the bosses 2, the flower and feather-work extending somewhat nearer the bottom of the receptacle than the bosses.

I claim—

The design for the ornamentation of table-ware, consisting in the bottom-forming swell A, a contracted portion A', connecting the bottom swell with an upperswell A², provided at its upper end with a mount A³ of conventionalized feathers and shells, the surface of the receptacle having curved flutings, some terminating on the bottom swell in bosses and others there terminating in curves treated with conventionalized feathers and flowers, 50 the feather-work and flower-work being flanked by the bosses, all as described and shown.

ARTHUR J. STONE.
